Morgan Stinemetz Inventor

UNITED STATES PATENT OFFICE.

MORGAN STINEMETZ, OF WASHINGTON, DISTRICT OF COLUMBIA.

DESIGN FOR A STATUETTE.

47,704.

Specification for Design.

Patented Aug. 10, 1915.

Application filed June 12, 1915. Serial No. 33,806. Term of patent 8½ years.

To all whom it may concern:

Be it known that I, MORGAN STINEMETZ, a citizen of the United States, residing at Washington, in the District of Columbia, have invented a new, original, and ornamental Design for Statuettes, of which the following is a specification, reference being had to the accompanying drawing, forming part thereof.

view, and Fig. 3 a top view of a statuette showing my new design.

I claim:

The ornamental design for a statuette, as shown.

MORGAN STINEMETZ.

Witnesses:

W. F. WOOLARD,

Wm. N. FISHER, Jr.
